(57) **CLAIM**

We claim the ornamental design for the slow pitch swivel jig, as shown and described.

DESCRIPTION

FIG. 1 is a top view of a slow pitch swivel jig.

FIG. 2 is an enlarged front-end view of the slow pitch swivel jig.

FIG. 3 is an enlarged rear-end view of the slow pitch swivel jig.

FIG. 4 is a left-side view of the slow pitch swivel jig (the right-side view being a mirror image of the left-side view); and,

FIG. 5 is a perspective view of the slow pitch swivel jig. The broken lines in the drawings illustrate portions of the slow pitch swivel jig which form no part of the claimed design.
